MAGNETICALLY CONTROLLED ELECTRON
DISCHARGE DEVICE

Hans Erich Hollmann, Berlin, Germany, assignor
to Telefunken Gesellschaft für Drahtlose Tele-
graphie m. b. H., Berlin, Germany, a corpora-
tion of Germany

Application June 27, 1935, Serial No. 28,645
In Germany July 5, 1934

4 Claims. (Cl. 250—27.5)

My invention relates to electron discharge de-
vices intended for generating very high frequency
oscillations and it is the principal object of my
invention to provide improved cooling means for
5 such devices.

As is well-known the so-called magnetron,
particularly the so-called split anode magnetron
in which the anode is divided into two or more
10 segments, is an excellent generator of ultra-
short and micro-waves. The phenomena oc-
curring in the tube resemble those of the Bark-
hausen arrangement employing a retarding field
circuit except that the electrostatic retarding
15 field of the anode is replaced in the magnetron
by the axial magnetic field.

The efficiency of the magnetron is considerably
improved if the electrodes are tuned to the fre-
quency of the oscillations to be produced because
20 the resonant voltages arising at the electrodes
will then react with greatest effect upon the
electron movement to produce the oscillations.
Resonant voltages on the electrodes at high fre-
quencies are desired, and this in turn necessi-
25 tates minimization of electrode capacity. The
electrodes, however, should not be made too small
for this would decrease the useable power or
output of the magnetron. The two anode seg-
ments are each provided with wire leads which
30 extend in both directions from the anodes and
terminate in parallel wire systems regardless of
whether the latter are short-circuited at the ends
or connected with a load.

The load capacity of the magnetron is gov-
erned principally by the permissible maximum
35 temperature of the plate segments and by heat
exchange or equalization. In order that the en-
ergy loss dissipated by the anode may be in-
creased, thereby increasing the useable power,
I provide in the preferred form of my invention
40 an arrangement wherein the parallel wire leads
supporting the two anode segments consist of
small diameter tubes thru which a cooling liquid
or gas flows. The advantage residing in this
novel arrangement over the cooling methods in
45 general use in radio frequency work and in which
the cooling liquid or fluid is in direct flowing
contact with the anode resides in the fact that
the cooling is effected without any incidental
impairment of the oscillations of the parallel
50 wires and the electrodes, and without causing
any dielectric losses.

The novel features which I believe to be char-
acteristic of my invention are set forth with
particularity in the appended claims, but the in-
55 vention itself will best be understood by reference

to the following description taken in connection
with the accompanying drawing in which Fig-
ure 1 is a perspective view of one form of an
electron discharge device embodying my invention,
and Figure 2 shows a modification of the 5
electrode and support shown in Figure 1.

In Figure 1 the two anode segments A and A'
are coextensive with and surround the coaxial
cathode K. The coaxial magnetic field is fur-
nished from a magnetizing coil 5. The anode
10 segments are supported by two support and lead
wires in the form of Lecher wires L and L' which
extend lengthwise thru the envelope E of the
magnetron and which in accordance with the
invention are tubular so that a cooling medium
15 can be circulated thru them. In order that the
heat generated thruout the entire anode seg-
ments may be dissipated more efficiently by the
cooling support tubes, transverse ribs or fins Q
are welded fast to the anode segments, inci-
20 dentally imparting to the latter high mechanical
strength.

Under some conditions maximum heating oc-
curs at the edges of the anode segments during
25 operation. In order to compensate for this con-
dition, the cooling action is extended along the
edges of the anode segment. In accordance with a
modification of my invention the tube supports
M as shown in Figure 2 are provided with paral-
30 lel branches M'—M' secured near the edges of
the anode B. In order that any small thermal
expansion which may incidentally take place may
be compensated for to avoid strain at the seals,
the tubular leads are sealed at one end in the
35 glass wall of the magnetron tube as shown in
Figure 1 by two bellows-like members K, K'
which may be of glass and which are sealed to
the tubes at one end and to the glass envelope
at the other. The cooling method here disclosed,
40 of course, is not confined to split anode types of
magnetron tubes; it may just as readily be used
where more than two anode segments are at-
tached to and supported by tubular Lecher wires
or leads in any desired arrangement.

While I have indicated the preferred embodi-
ments of my invention of which I am now aware
and have also indicated only one specific appli-
cation for which my invention may be employed,
it will be apparent that my invention is by no
means limited to the exact forms illustrated or
50 the use indicated, but that many variations may
be made in the particular structure used and the
purpose for which it is employed without de-
parting from the scope of my invention as set
forth in the appended claims.

What I claim as new is:—

1. An electron discharge device having an envelope containing a thermionic cathode and a plurality of anodes surrounding said cathode and supports for said anodes comprising tubular members, each of said members extending thru and sealed in opposite ends of the envelope and attached to and supporting said anodes intermediate the ends of said envelope, said tubular members providing a path for a cooling fluid and constituting the leads for said anodes.
2. An electron discharge device comprising an envelope, a straight thermionic cathode within said envelope, segmental anodes positioned around and coaxially with said thermionic cathode, tubular members of small diameter extending thru and having one end sealed to one end of said envelope and supporting said segmental anodes, the other end of said tubular members extending thru the other end of the envelope and bellows members sealed to the glass and to other end of said tubular members whereby said tubular members may expand and contract in response to temperature changes when a cooling medium is circulated thru said tubular members.
3. An electron discharge device comprising an

elongated envelope, a straight thermionic cathode within said envelope, segmental anodes positioned around and coaxial with said thermionic cathode, lead-in and support conductors secured to said segmental anodes and comprising tubular members of small diameter extending thru opposite ends of said envelope, one end of each of said tubular members being sealed directly to the envelope and a bellows member sealed to the envelope and to the other end of each tubular member whereby expansion and contraction of said tubular members can take place in response to temperature changes when a cooling medium is circulated thru said tubular members.

4. An electron discharge device comprising an elongated envelope, a thermionic cathode within said envelope, segmental anodes positioned around said thermionic cathode, tubular support members for said anodes extending thru opposite ends of said envelope and provided intermediate their ends with a pair of oppositely disposed tubular portions secured adjacent the edges of the segmental anodes whereby said segmental anodes are cooled when a cooling medium is circulated thru said tubular support member.

HANS ERICH HOLLMANN.
